UNITED STATES PATENT OFFICE

EDWARD J. SHAEFFER AND EUGENE P. BROWN, OF WHITING, INDIANA, ASSIGNEES TO
STANDARD OIL COMPANY, OF WHITING, INDIANA, A CORPORATION OF INDIANA

CRACKING SYSTEM

Application filed March 8, 1924. Serial No. 697,755.

The present invention relates to improvements in the production of low boiling point hydrocarbon oils from higher boiling point hydrocarbon oils by pyrolytic decomposition, and will be fully understood from the following description illustrated by the accompanying drawing, in which a layout of apparatus suitable for carrying the invention into effect is diagrammatically shown.

10 Referring more particularly to the drawing, the numeral 5 indicates a furnace setting in which are mounted the preheating coil 6 and the heating coil 7, the former being connected with the latter by means of the pipe 8. 15 A second setting 9 is provided, in which is mounted a digester coil 10, which is connected with the outlet of the heating coil 7 by means of the connecting pipe 12. To the outlet of the digester coil 10 is connected a pipe 13, which 20 may suitably be provided with a gas cushion device 14 to take the shock of variations in the hydraulic pressure of the oil passing through the system.

25 The pipe 13 discharges into a vaporizing chamber 15, which may suitably be of the form of a horizontal cylinder, although the precise shape employed for this vaporizing chamber or drum is not material. A pressure relief valve 16 is provided in the line 13 before 30 it enters the vaporizing chamber 15, which is maintained at a lower pressure than the heating and digesting coils. The pipe 13 terminates within the drum 15 in a perforated distributing pipe 17, which is well below the liquid level maintained in the drum. Suitable 35 means, such as the float indicator 18, are provided for determining the position of the liquid level in the drum.

40 From the vaporizing drum 15 vapors pass out through a separator 19 of any suitable type, for removing and returning entrained liquid, and through an outlet pipe 20, which leads into the lower portion of a tower 21, which may suitably be a screen or baffle tower. 45 Feed stock or other suitable material may be introduced into the upper portion of the baffle tower 21 through a supply pipe 22, as herein-after more fully described. Partial condensation takes place in the tower 21, and condensate formed therein, together with the

cooling liquid introduced through the pipe 22, is withdrawn from the base of the tower 21 through the outlet pipe 23. A suitable device, such as the float indicator 21^a, is provided for control of the liquid level in the 55 tower 21. Vapors pass out from the top of the tower 21 through a vapor conduit 24, which leads them into the base of a dephlegmating tower 25, which may suitably be of baffle plate or bubble plate type, and in the fractionating 60 tower 25 a further cooling of the vapors takes place, with a formation of condensate. The condensate thus formed is discharged from the base of the dephlegmating column 25 through an outlet pipe 26 into the base of the 65 tower 21, and is withdrawn from the latter, together with reflux formed therein, through the outlet pipe 23.

From the top of the fractionating column 25 vapors pass through the line 27 into a 70 reflux drum or tower 28, in which they are cooled by indirect heat exchange with a suitable cooling medium, preferably fresh stock intended for introduction into the system. Any condensate formed in the reflux drum 75 28 is discharged through the pipe 29 into the upper portion of the fractionating column 25, through which it descends in countercurrent to the rising vapors. From the top of the reflux drum 28 vapors pass through 80 the vapor line 29^a into a vapor heat exchanger 30, from which vapor and condensed liquids pass through a condenser 31. From the condenser 31 condensate and gas pass into a receiving drum 32. This drum is provided with 85 a liquid discharge line 33, in which is placed a meter 34 and a pressure release valve 35. Gas is discharged through the pipe 36 provided with a pressure release valve 37, by means of which pressure is retained upon the 90 vaporizing and condensing system.

Liquid residue or tar is discharged from the vaporizing drum 15 through a line 38 provided with a pressure release valve 39 into the lower portion of a vaporizing drum 40, this 95 drum being suitably provided with baffles or screens. The tower 40 being at a lower pressure than the drum 15, a further vaporization of the tar takes place, the separated vapors passing out through vapor line 41 into con- 100

denser 42, from which the condensate passes to a receiving drum 43. The pressure tar distillate collected in the receiving drum 43 is discharged through a line 44 in which are provided a meter 45 and a pressure relief valve 46. Residues are withdrawn from the tower 40 through a line 47 provided with a release valve 48.

The stock to be treated is brought in through line 49 and is forced through the heating system by the pump 50. By the pump 50 the stock is forced through a line 51 to the vapor heat exchanger 30, from which the partially heated stock passes into the feed line 52. A valved branch line 53 leads from the line 51 to the reflux drum 28, in which are provided suitable heat exchanger devices, such as the coils 54, through which the feed stock passes to provide the desired cooling effect upon the vapors passing through the drum. After leaving the reflux drum 28, the feed stock passes through the pipe 55 into the feed line 52.

A second valved branch line 56 leads from the line 51 to the pipe 22 by which stock is supplied to the tower 21 for cooling action therein. A valved line 57 connects this supply pipe 22 with the feed line 52, and by suitable control of the valves in the lines 56 and 57, the temperature of the feed stock entering the tower 21 may be controlled. By this means the temperature of the vapors leaving the tower 21 may be adequately controlled and a direct heat exchange is secured within the tower, resulting in a condensation of the heavier or higher boiling portions of vapors passing therethrough. This feed stock is discharged through the pipe 23, together with reflux formed in the tower 21 and in the dephlegmating column 25. The liquids thus discharged through the pipe 23 are forced by a pump 58, preferably of the surge pump type, through a line 59 into the feed line 52. The feed line 52 is connected with the inlet of the preheating coil 6.

In carrying out the present process, the stock to be treated, which may suitably be a heavy hydrocarbon oil of the nature of gas oil or a crude residuum is drawn in from the pipe 49 and forced by the pump 50 under pressure into the line 51 leading to the heat exchanger 30. From the heat exchanger the stock, partly heated therein, passes through the line 52 to the preheating coil 6, in which it is pre-heated to a temperature below cracking temperature by the combustion gases which have already been used to heat the primary heating coil 7 and the digester coil 10. From the preheating coil 6 the oil, suitably heated therein to a temperature of, say, 500 to 600° F., is forced through the pipe 8 into the heating coil 7, in which it is brought to a cracking temperature in excess of 675° F., say 850 to 900° F., while flowing therethrough with a velocity such that substantially no deposit

of carbon can take place within the coil. From the heating coil 7 the hot oil passes through the pipe 12 into the digesting coil 10 in which it is held at substantially the same temperature as that to which it is brought in the coil 7 by any suitable heating means, a relatively moderate heat being required for this purpose. The oil is caused to travel through the digesting coil 10 at a rate such that substantially no deposition of carbon can take place, and is maintained therein for a sufficient period for a substantial amount of cracking to take place.

The digesting coil has preferably a somewhat larger cross sectional area than the heating coil 7 and is also of somewhat greater length, thereby providing more capacity and longer travel of the oil through the digesting coil than through the heating coil. The rate of travel through both coils is sufficiently high to prevent deposition of coke, and the digesting coil 10 being only mildly heated to maintain a cracking temperature therein. Suitable dimensions for heating and digesting coils in a plant having a capacity of 60 barrels per hour are, respectively 4500 feet of 3 inch pipe and 6000 feet of 4 inch pipe. These dimensions may, of course, be varied within wide limits.

The oil passes from the coil 10 through the line 13 provided with a gas cushion 14 for suitably cushioning hydraulic shocks in the system, and after passing the pressure release valve 16, enters the vaporizing drum 15. The pressure release valve 16 is so adjusted as to maintain in the heating and digesting coils, a pressure such that the stock is maintained in substantially liquid state until a material amount of conversion has taken place; for example, a pressure of 200 to 600 pounds per square inch may be employed. A suitable pressure with stocks of the character of gas oil has been found to be about 325 pounds per square inch. In the vaporizing drum 15 a pressure above atmospheric is also maintained, the pressure therein being suitably 25 pounds per square inch or higher. Any intermediate pressure between atmospheric and pressure maintained in the heating and digesting coils may be employed. A body of liquid is maintained in the drum 15, and this body of liquid is kept by the incoming hot oil at a temperature of from 100 to 200° below that prevailing at the outlet of the digesting coil; that is, with a temperature of 850 to 900° in the digesting coil, the liquid in the vaporizing drum will have a temperature of about 700° F. The pipe 13 terminates in the drum 15 in a distributing pipe 17 near the bottom of the drum and well below the surface of the liquid body therein. The release of pressure upon the liquid entering the drum causes a rapid vaporization of a considerable portion thereof, say from 40 to 80%, and the introduction of the oil into the vaporizing

drum in this manner causes a violent agitation of the liquid body therein and causes any coke formed in the oil body to be kept in suspension therein. The formation of deposits of coke in the vaporizing drum is thereby substantially prevented.

The large amount of vapors evolved in the drum 15 passes out through a separator 19, which removes and returns entrained liquid to the drum, and the vapors then pass through the line 20 into the tower 21, in which they are slightly cooled, partly by radiation from the tower and partly by the introduction into the tower of a suitable cooling medium, preferably hydrocarbon oil, such as a part of the stock to be treated. In the embodiment of the invention shown in the drawing, this cooling medium is supplied to the tower through the pipe 22, and may be drawn at will through the pipe 56 from the fresh charging stock line 51 or from the pipe 57 connecting with the charging stock line 52 containing the stock partly heated as it passes through the heat exchanger 30, or partly from both, in accordance with the temperature conditions which it is desired to obtain within the tower 21. The supply of the cooling medium is suitably controlled to bring the temperature of the vapors in the tower 21 to 600 to 700° F. and to thereby remove from the vapors a considerable proportion of the heavier constituents before the vapors pass into the bubble tower or fractionating column 25 in which a more careful fractionation thereof is effected. The reflux formed in the tower 21, together with the hydrocarbon oil used as a cooling medium therein, pass out through the pipe 23 and are forced by the pump 58 into the charging stock line 52 leading into the coils.

From the tower 21 the vapors, cooled to 600 to 700° F., pass into the fractionating column 25, in which a further cooling takes place. From the column 25 the vapors pass into a reflux drum or condenser 28, where they are subjected to a controlled cooling by heat exchanger with cold charging stock drawn from the line 51 through the valved line 53. The supply of cooled charging stock to the condenser or drum 28 is controlled in accordance with the character of the end product desired, which may suitably be finished gasoline or, if desired, a somewhat heavier product intended to be subsequently rerun into finished products. Condensate formed in the condenser or reflux drum 28 returns to the top of the fractionating column 25 through the line 29 and descends through the column together with any reflux formed therein. The reflux formed in the column 25 and in the drum 28 is drawn off through the line 26, and passes, together with the condensate and cooling medium from tower 21, to the charging stock line 52 in the manner already described. The vapors from the con-

denser or reflux drum 28 pass through line 29a and heat exchanger 30 and condenser 31, in which the final distillate product is condensed. From the condenser 31 the distillate product, together with any permanent gas formed in the process, passes into the receiver 32. Distillate may be drawn off from the latter through the line 33 and gas passes off through the line 36, which is provided with a pressure valve 37 which reduces the pressure of the gas to that desired in the line 36, for example, atmospheric or slightly thereabove. The valve 37 is employed to maintain the desired pressure in the vaporizing drum 15 and in the overhead system just described.

The residuum or tar in the vaporizing drum 15 passes out through the line 38 provided with the pressure release valve 39 into a vaporizing tower 40, which is maintained at a substantially lower pressure, say at atmospheric pressure or slightly thereabove. A pressure slightly in excess of atmospheric, say 10 to 15 pounds, is preferred, as the use of such pressure obviates the necessity of pumping unvaporized liquid from the tower 40. The reduction of pressure on the hot residuum or tar permits of a further vaporization thereof in the tower 40 without the supply of added heat to a bottom of, say, about 10% on the original stock, in which most of the coke formed in the process is accumulated. The vaporized portion passes through a vapor line 41 into the condenser 42, and the condensate passes into the drum 43 and may be employed as a part of the charging stock for the system or may be used as a fuel as desired. The bottom or residuum formed in the tower 40 is forced out through the line 47, the liquid level in tower 40 being maintained as indicated by float indicator 58. The temperature of the residuum within the tower 40 may be from 400 to 600° F., being substantially below cracking temperature.

We claim:

1. The method of producing low boiling hydrocarbon oils from higher boiling hydrocarbon oils which comprises forcing such oil in a rapid stream through a heating zone maintained at such a temperature as to bring the oil to cracking temperature, immediately passing the oil into and through a confined passage subjected to moderate heat sufficient only to maintain the oil at substantially the same cracking temperature, the rate of flow of the oil being sufficient to prevent substantial deposition of coke or carbon, maintaining a pressure upon the oil sufficient to retain the oil in substantially liquid state until a material amount of decomposition has been effected, introducing the oil products entirely and directly into a chamber at lower pressure, maintaining a liquid body of oil products in said chamber, the point of introduction of heated oil thereinto being below the level

110

of the liquid body, and separating the vapors evolved in said chamber.

2. The method of producing low boiling point hydrocarbon oils from higher boiling point hydrocarbon oils which comprises passing the oil to be treated in a confined stream through a heating zone at a temperature sufficient to bring the oil to cracking temperature, then passing the oil in a confined stream through a zone heated sufficiently to maintain the oil at substantially the same cracking temperature, maintaining pressure upon the oil sufficient to keep the original stock in liquid state under the temperature conditions prevailing, the velocity of the oil in passing through said heated zones being such as to prevent substantial deposition of carbon therein, introducing the heated oil products entirely and directly into a body of liquid cracked oil products maintained at a lower pressure above atmospheric pressure, whereby a separation of vapors is effected and carbon formed is maintained in suspension in the liquid residuum in said chamber, and withdrawing liquid residuum from said chamber.
